tion of Wisconsin

Application December 21, 1942, Serial No. 469,615

14 Claims. (Cl. 284—4)

1

My invention relates to improvements in fluid carrying, transferring, and shut-off devices.

My invention is of importance in providing for fluid transfer where a substantially permanent conduit connection is desired, but where instantaneous disconnection of the fluid transfer device is sometimes necessary, and where means for preventing loss of fluid and maintenance of certain safety standards are required.

In the description of my invention hereinafter set forth, I shall use as an example of a fluid transfer problem that which prevails in the transfer of liquid fuel from a supplementary fuel can on an army tank to the main fuel reservoir within the tank. It is an important feature of my invention that I have provided means for jettison mounting and jettison discard of the auxiliary can and portions of the transfer conduit and connections in such an installation.

Broadly, the objects of my invention are to provide a jettison can, means for fluid transfer from such a can, means to facilitate jettison of the can, and severance and shut-off means for the transfer conduits.

Further objects of my invention will be explained in greater particularity and will be apparent from the following description of my improvements.

In the drawings:

Figure 1 is a plan view, somewhat diagrammatic, showing an army tank, my jettison can, connections, and jettison controlling means.

Figure 2 is a section on line 2—2 of Figure 1.

Figure 3 is a side elevation of my jettison can and its mounting and releasing means, with a fragmentary showing of a portion of the army tank.

Figure 4 is a vertical section through the fluid receptor and fluid-feed terminal of my fluid transfer device, the yoke for holding the parts in releasable assembly being shown in elevation.

Figure 5 is a plan view of my assembled receptor and feed terminal.

Figure 6 is a vertical section through my feed terminal and a portion of the conduit associated therewith.

Figure 7 is a side elevation of my receptor with portions thereof broken away in vertical section, the yoke being hingedly "retracted" in readiness for the reception of the feed terminal shown in Figure 6.

Like parts are designated by the same reference characters throughout the several views.

Certain features of my fluid transfer devices herein described have some reference to conduit

2

connections as described in my pending patent application Serial No. 395,728, filed May 29, 1941, on "Fluid transfer devices," but my invention herein described relates more particularly to provisions for the breaking of the connection of fuel supply and fuel receiving units.

An army tank 10 obviously has a limited capacity in its fuel reservoir 11, and military requirements necessitates the provision of some form of auxiliary or supplemental fuel supply capacity exterior of the tank. Obviously, when military combat commences, the auxiliary supply can must be discarded since it impedes military operation of the tank. I have, therefore, provided means whereby an auxiliary can 12 may be jettisoned instantly and the fluid-supply connections may be disconnected instantly without loss of fuel and without danger of fuel explosion.

The logical place for an auxiliary fuel can on 20 the modern military tank 10 is within the sweep of cannon 13 mounted in turret 13a, and obviously the can must be disposed of before the military necessity requires that the gun 13 swing through its entire orbit. I, therefore, provide a jettison 25 can mounting 14 upon which the can 12 is biased by gravity so as to be completely insecure. To this mounting I secure the can 12 by means of straps 15 which are permanently attached at 16 to the mounting 14 and are releasably attached at 17 by means of jettison clips 18. These jettison clips are somewhat hinge-like in appearance and have a pintle 19 which when pulled out of position will sever the connection between the mounting 14 and one end of each of the straps 15, thus permitting the can to fall from the mounting. Each of the pintles 19 is provided with a lanyard 20 passing over a suitable sheave 21 and extending through a hawse pipe 22 to a position within the tank where a soldier may pull it. I thus provide an auxiliary can for fuel and provide the means whereby the can may be jettisoned, but a problem is presented with reference to the disconnection of means for fluid transfer from the auxiliary can 12 to the fuel reservoir 11. It is here that arrangement must be made for disconnection of the transfer conduit and still preserve the safety and freedom from loss of fuel referred to above.

While the tank 12 is in position on support 14 and secured there by the straps 15, a flexible conduit 25 in fluid connection with the can 12 extends to and is in fluid-tight fluid-transfer relation to a filler unit 26 for the fuel reservoir 11. It is to this fluid transfer and fluid-tight connection that attention is now directed. The general

configuration of the cap 21 for the filler unit 26 is conventional in that it comprises a threaded cap portion 28 and extended lugs 29 and 30 for manual threaded engagement with a thimble 31 extending into the reservoir 11. Centrally of the cap 28 there is a recess 32 marginally bounded by depressed portion 33 of the cap, threaded at 34 to receive a receptor sleeve 35 in which I house the valve mechanism to prevent spillage, to provide safety against explosion, and to provide bleed connections for the transfer of air or gases when the reservoir 11 is receiving fuel or is delivering fuel.

The largest structural element in the receptor 35 is a stemmed valve-like element which I shall term the poppet gate 36, the stem 37 of which is guided in a guide plug 38 at the bottom of the receptor sleeve 39. The margin of the top of the poppet gate has a sliding fit in sleeve 39 and is provided with a soft valve plug ring 40 to seat against the receptor closure seat 41 in the uppermost extent of movement of the poppet gate. When thus seated, the top of the poppet gate provides a positive closure with the exception of the provision for gas bleed hereinafter to be described.

The poppet gate is urged toward its closed position by two springs, one of which is a poppet gate spring 42 and the other of which is a jettison spring 43. The jettison spring is shorter than the poppet gate spring, of heavier spring wire, and generally "stronger" than the poppet gate and is intended to give a violent upward thrust upon the poppet gate when a jettison operation is being accomplished. The poppet gate spring 42 on the other hand is of relatively light spring wire, is longer, and carries out the complete poppet gate closure to bring the cushion ring 40 against the seat 41 after the quick thrust of jettison disconnection of the parts has been accomplished.

To compensate for the withdrawal of fuel from the reservoir in normal operation of the motors fed by the reservoir, I provide for passage of gases into the reservoir from the outside atmosphere and, using the same openings, permit escape of gases under pressure from the reservoir under certain conditions.

For escape of gases from the reservoir, ports 47 pass the gases to a hollow space 45 in the poppet gate itself. From the space 45, gases pass through duct 46 to the outside atmosphere. In the reverse direction, atmospheric gases may pass through duct 46, space 45 and ports 47. In the event of expansion of fuel due to heat or otherwise, the excess pressure in the reservoir may be vented through the ports 47, space 45 and duct 46. Within the chamber 45 I provide a float 48 with float stem 49. When the liquid fuel in the reservoir 11 approaches the top of the reservoir, liquid fuel may enter the chamber 45, elevate the float 48 and its stem 49 to bear against a ball check 49' and urge it to its seat, thus completely closing the reservoir even as to gas bleed, and preventing losses and possible explosion in the event that the tank 10 is tipped over or any conditions exist to promote spillage of fuel.

To establish connection between the parts described above and the transfer conduit 25, I provide a bleed terminal for the transfer conduit 25, the purpose of which is to establish fluid and gaseous bleed connection between the transfer conduit and the fuel reservoir. The parts of this feed terminal will now be described, it being understood that the function of such parts, while including the obvious liquid fuel transfer and gas

bleed, also include provision for jettison disconnection.

The principal external parts of the feed terminal include a hood 50 and a tubular delivery nozzle 51. A part of the hood extends laterally tubularly at 52 to provide a hose connection for the transfer hose 25. The external dimension of the nozzle 51 at 53 is a sliding fit in the upper portion of the receptor sleeve 35, but the extended end 54 of the delivery nozzle is of smaller diameter to provide for the ready reception and the manipulation of the nozzle as it is inserted into the receptor sleeve. Marginally of the hood, which is in liquid-tight relation to the nozzle, as shown clearly in Figure 6, I have provided a wedge-shaped bearing ring 55 which may seat upon a gasket 56 in the upper face of the end of the receptor sleeve 35, thus establishing liquid-tight relationship between the feed terminal and the receptor when the hood is under pressure, as will be hereinafter described.

Within the hood and delivery nozzle I provide a feed valve 60 with a central valve stem 61 guided in a guide tube 62 spaced from the walls of the nozzle by spider webs as seen in Figure 4 at 63. In the upper portion of the guide tube I provide a feed valve spring 64 to bear upon the stem 61. The feed valve spring 64 is thus urged to its seat in much the same manner that the poppet gate 36 is urged to its seat. Suitable gaskets, as indicated in the drawings, may be provided. The spring 64, while smaller in diameter than the poppet gate spring 42, is of heavier spring wire, and in the opposing forces incident to the insertion of my feed terminal in the receptor 35, the poppet gate spring is pushed down so as to push the poppet gate from its seat 41 before the spring 64 is compressed so as to open feed valve 60.

Because of the differing strengths of the jettison spring 43, the poppet gate spring 42 and the feed valve spring 64, the sequence of mechanical occurrences incident to the establishment of connection between the feed terminal and the receptor is as follows. As the extended end 54 of the delivery nozzle is received in the upper portion of the receptor sleeve 35 the feed valve 60 is closed and the poppet gate is closed. When the abutment tip 44 strikes the valve 60, the first spring to yield is the poppet gate spring 42, and the poppet gate will commence to open in the further insertion of the feed terminal. When the poppet gate contacts the jettison spring 43 the poppet gate will momentarily come to rest, since the combined strength of the poppet gate spring 42 and the jettison spring 43 exceeds the strength of feed valve spring 64, which, in the further movement of the parts toward ultimate fluid delivery and complete engagement is compressed to open the feed valve 60. By the time the feed valve initiates its opening movement, the portion of the nozzle 51 at 53 is by this time entering the upper portion of the receptor sleeve 35, and a sliding fit as above described provides good safety conditions for fluid delivery. Fluid commences then to flow through the feed valve 60, and as the parts are brought further into engagement the feed valve opens up to its completely open position. Then, in the further engagement of the parts, the jettison spring, and of course the poppet gate spring 42, are compressed.

To provide for transfer of air and gases from the reservoir through the feed terminal to compensate for liquid delivered from the feed terminal to the reservoir, I provide an air transfer passage at 65 into the guide tube 62, where, when

the central valve stem 61 is in the proper position for fluid delivery, it is connected with a T-shaped conduit 66 in said central valve stem. Air transfer may then be completed through this T-shaped conduit 66 past the feed valve spring 64 to a central hood tube 67. Within the flexible conduit 25 a separate flexible and extensible gas tube 68 is so disposed that it may fit over the hood tube 67, and this extensible gas tube 68 is used to carry the gases to the jettison can 12.

It will be noted that the stem 61 is undercut at 69 at a point where the undercut portion will be opposite the end of tube 65 when the valve 60 is open, but that when the valve 60 is closed there is no gas vent through tube 65 from the jettison can.

Tracing fluid flow from the conduit 25 into the fuel reservoir 11, it will be seen that the fluid passes from the conduit 25 through 52 into the interior of the hood 50, thence downwardly through the feed terminal nozzle and past valve 60 into the receptor 35, and since the receptor poppet gate is open, fluid will pass through the openings in the side wall of the apertured receptor sleeve. While fluid is thus passing into the reservoir, gases and air of course must be relieved. They will pass through tube 65 into the interior of stem 61 and through tube 67 and extensible tube 68 back to the jettison can 12.

It will be noted that the receptor sleeve 39, although of such diameter as to be in threaded engagement with the cap 28 at 34, has an upward extension in the recess in the cap 28, flanged outwardly at 70 to loosely engage a flange collar 71 which has upwardly extending ears 72. To these ears I hingedly connect a yoke 73, the central portion of which is provided with an adjusting screw 74, lock-nutted at 75 so that the adjusting screw may be seated at the correct position of adjustment to impinge solidly upon the top of the hood 50 when the feed terminal is in complete engagement with the receptor. It is obvious from the above description that when the parts are in complete engagement and the yoke is in the position shown in Figure 4, the jettison spring 43 is in full compression. I therefore make it possible by means of a lanyard connected to the yoke at 80 to quickly and easily dislodge the yoke hingedly from the position shown in Figure 4 to the position shown in Figure 7, and immediately the feed terminal will be ejected from the receptor by the jettison spring 43. Both fluid flow control valves (the poppet gate and the feed valve 60) will immediately be closed by their respective springs, and if the lanyard for jettison of the entire tank 12 has been pulled the tank with its supply tube 25 will be jettisoned.

It will be noted that the yoke 73 has a stop angle 81 to restrict it to a swinging motion of approximately 90 degrees, the stop angle assuring that the yoke cannot go beyond the vertical position in the one direction, thus assuring that a lanyard pull at 80 will not find the yoke in such position as to lock it over the hood.

In the top of the poppet gate 36 I provide a number of soft fuse plugs 82, which, in the event of fire, will melt and relieve pressure in any reservoir equipped with my fluid transfer device. Pressures developed under such conditions may exceed the relief capacity of the poppet bleed 46, or the excessive heat may be presented at a time when the ball check 49 is blockading the poppet bleed. The fuse plugs 82 will then serve their purpose to prevent excessive pressures.

I claim:

1. In a device of the character described, a conduit for fluid transfer provided with a feed terminal, a reservoir having a receptor, said terminal being receivable into said receptor for a complete engagement in fluid transfer position, a yoke to hold the terminal in said connected position, a valve in the receptor and a valve in the feed terminal provided with springs for immediate closure thereof upon removal of the terminal from the receptor, and a heavy spring in the receptor biased to thrust the terminal from the receptor.
2. A feed terminal telescopically receivable in a receptor, a receptor shaped for reception of the terminal whereby to provide fluid-tight relationship to the terminal and receptor when the two are in complete telescopic engagement, a poppet gate positioned within the receptor, whereby to provide fluid-tight closure of the receptor upon removal of the terminal, a valve for automatic closure of the terminal upon withdrawal of the terminal from the receptor, a light spring in the receptor to bias the poppet gate to closed position, a stronger spring for the valve in the feed terminal to close the valve in the terminal, whereby upon progressive engagement of the terminal and the receptor the poppet gate will open first, and a spring stronger than either of said poppet gate or terminal valve springs and positioned to bias the parts against final stages of progressive telescopic engagement, and a yoke to hold the parts in complete engagement and provided with means for quick release, whereby upon quick release said heavy spring will project the terminal from the receptor.
3. In apparatus of the character described, a union comprising two connector members meeting endwise, said members each having a liquid passage and a concentric gas passage, one of said members having valve means adapted to close the liquid passage and valve means adapted to close the gas passage, both of said valves being biased toward closing position, means for opening both of said valves when the members of the union are brought into operative relation, and means for locking the union members in operative relation.
4. In apparatus of the character described, a union comprising two connector members meeting endwise, said members each having a liquid passage and a concentric gas passage, one of said members having valve means adapted to close the liquid passage and valve means adapted to close the gas passage, both of said valves being biased toward closing position, means for opening both of said valves when the members of the union are brought into operative relation, means for locking the union members in operative relation, and means operable from a remote point for releasing said locking means thereby permitting said members to separate and said valves to close.
5. In apparatus of the character described, a union comprising two connector members meeting endwise, a valve in each of said members, means for locking said members together in connected relation, and a spring in each of said members tending to close the valve of that member, said valves comprising portions which interengage to unseat the valves when the members of the union are brought together in operative relation, the spring of one of said members being stronger than the spring of the other member, and an abutment to limit the extent to which the valve of the latter member may be opened.
6. In apparatus of the character described, a

union comprising two connector members meeting endwise, said members each having a liquid passage and at least one of said members having a concentric gas passage, one of said members having valve means adapted to close the liquid passage, and valve means adapted to close the gas passage, both of said valves being biased toward closing position, means for opening both of said valves when the members of the union are brought into operative relation, and means for locking the union members in operative relation.

7. In apparatus of the character described, a union comprising two connector members meeting endwise, said members each having a liquid passage and a gas passage, one of the members having valve means adapted to close the liquid passage, and valve means adapted to close the gas passage, both of said valves being biased toward closing position, means for opening both of said valves when the members of the union are brought into operative relation, and means for locking the union members in operative relation.

8. In apparatus of the character described, a union comprising two connector members meeting endwise, said members each having a liquid passage and a gas passage, the gas passage and the liquid passage of one of said members being concentric, one of said members having valve means adapted to close the liquid passage, and valve means adapted to close the gas passage, both of said valves being biased toward closing position, means for opening both of said valves when the members of the union are brought into operative relation, means for locking the union members in operative relation, and means operable from a remote point for releasing said locking means, thereby permitting said members to separate and said valves to close.

9. In apparatus of the character described, a union comprising two connector members meeting endwise, said members each having a liquid passage and a gas passage, one of said members having valve means adapted to close the liquid passage and valve means adapted to close the gas passage, both of said valves being biased toward closing position, means for opening both of said valves when the members of the union are brought into operative relation, means for locking the union members in operative relation, and means operable from a remote point for releasing said locking means thereby permitting said members to separate and said valves to close.

10. In apparatus of the character described, a union comprising two connector members meeting endwise and each provided with a liquid passage, one of said members also having a gas passage and having valve means biased toward closing position for closing both its liquid and gas passages, means for opening said valve means when the members of the union are brought into operative relation, locking means for holding the union members in operative relation, said locking means including a control member for releasing said locking means and having limited movement in which said locking means is engageable and disengageable, and means operable from a remote point and connected with said control member for the release of said locking means, the bias on said valve means assisting in the separation of said members in the closing of the valve means.

11. In apparatus of the character described, a union comprising two connector members meeting endwise, said members each having a liquid passage, valve means controlling the respective liquid passages of the members, spring means biasing said valve means toward their respective closed positions, means for opening both of the valve means against their respective spring means when the members of the union are brought into operative coupling relation, said spring means being sufficiently strong to tend not only to close the respective valve means but to dislodge the said members from their fully coupled relation, locking means for holding said members in fully coupled relation against the bias of said spring means, said locking means including a quickly releasable detent and means including a flexible connector operable from a remote point for releasing said detent, whereby to unlock said members for at least partial separation thereof under the bias of said spring means, said valves closing in the uncoupling movement of said members.

12. In apparatus of the character described, a union comprising a pair of coupling members, each having a liquid passage, a valve seat and a valve, means for opening the valves when the coupling members are brought into operative coupling relation, quickly releasable detent means for locking said members releasably in coupling relation, means operable from a remote point for releasing said detent means, whereby to unlock the coupling between said members, and spring means for closing the respective valves of said members and effecting movement of separation between the members upon the release of said detent means.

13. The device of claim 12 in which the spring means acting on the valve of one of said members is stronger than the spring means acting on the valve of the other, and an abutment limits the extent to which the latter valve may be opened before dislodging the valve having the stronger spring means.

14. In apparatus of the character described, a union comprising a pair of coupling members in detachable connection, each having a liquid passage, a valve seat and a valve, the respective valves being provided with means engageable in the coupling of said members, said valves opening oppositely in their respective members and adapted to be opened when said members are fully coupled, spring means acting on the valves individually in a direction to bias them toward their respective seats, the spring means acting on the valve of one member being materially stronger than the spring means acting on the valve of the other, whereby said other valve will be the first to be opened in the coupling of said members, a stop limiting the opening movement of the valve last mentioned whereby to force open the valve having the stronger spring, a quickly releasable detent constituting means for locking said members in coupled relation whereby to hold said valves open, the spring means acting on the respective valves tending to separate said members upon the release of said detent, and means including a flexible element operable from a remote point connected with said detent for the release thereof, whereby to permit said members to be separated in accordance with the bias of the spring acting upon their respective valves.
